UNITED STATES PATENT OFFICE.

MARK S. HOTCHKISS, OF BINGHAMTON, NEW YORK.

STAKING DEVICE FOR ROAD-RAILS.

1,349,340.

Specification of Letters Patent. Patented Aug. 10, 1920.

Application filed January 27, 1920. Serial No. 354,351.

To all whom it may concern:

Be it known that I, MARK S. HOTCHKISS, of Binghamton, in the county of Broome, in the State of New York, have invented new and useful Improvements in Staking Devices for Road-Rails, of which the following, taken in connection with the accompanying drawings, is a full, clear, and exact description.

10 This invention relates to certain improvements in forms for supporting concrete and analogous materials while in a green state during the process of construction and is particularly useful in forming the edges of 15 sidewalks, road beds and similar work.

The main object is to provide a form of this character which may be easily and quickly installed and firmly held in its operative position with a minimum amount of 20 labor or may be quickly removed and reused in the progressive construction of other parts of the work.

Another object is to make the form and its braces or stays in separate sections capable of being readily attached to or detached from one another so that the main body of the form may be used to support different parts of the concrete work without or with 25 different forms of stays.

30 A further object is to enable the same braces and stays to be used with different sizes of forms by rendering them relatively adjustable.

Other objects and uses relating to specific 35 parts of the apparatus will be brought out in the following description.

In the drawings:

Figure 1 is a longitudinal sectional view of the preferred form of my invention as 40 supporting the upright sections of walks and the like.

Fig. 2 is a perspective view of the same device showing a relatively short length of the main body.

45 Fig. 3 is a sectional view similar to Fig. 1 except that the diagonal base plate is omitted.

The form shown is adapted to be used for supporting the upright edges of a concrete 50 body —A—, such as a side walk, pavement or analogous structure and comprises a main body —1— brace plates —2— and —3—, a brace bar —4— and stake plates —5— and —6— all of which parts are preferably

made of sheet metal although they may be 55 made of any other suitable material.

The main body —1— preferably consists of an elongated plate of angular cross section having an upright portion —7— and horizontally extending portions —8— and 60 —9— constituting flanges projecting upwardly from the upper edges thereof, the upper flange having its free edge —10— turned downwardly and is provided with one or more slots —11— for the reception 65 of the adjacent end of the brace plate —2—.

The lower horizontal flange —8— is also provided with one or more slots —12— for the reception of the lower end of the stake plate —5— which passes through similar 70 slots —13— and —14— in the brace plates —3— and —2—, respectively.

The inner end of the brace plate —2— is reduced in width to form a tongue —15— and shoulders —16— at opposite sides 75 thereof, the tongue —15— being of substantially the same width as the slot —11— through which it passes and is deflected upwardly at an angle to the main portion of the plate —2— to engage the inner face of 80 the downwardly projecting portion —10— of the flange —9— while the shoulder —16— engages the outer face of the same flange.

When the plate —2— is interlocked with 85 the flange —9— in the manner just described, it is held against endwise movement by the upturned end of the tongue —15— and shoulders —16— and may be easily withdrawn from interlocking engagement 90 with the flange —9— by simply rocking its outer edge upwardly and then withdrawing the entire plate outwardly, these parts being interlocked by reversing this operation.

The brace plate —3— is hinged at one 95 end to the plate —2— by a pivotal pin —17— and extends downwardly and inwardly from the pivot so as to engage the plate —1— at the junction of the parts —7— and —8— thereby holding the outer 100 end of the plate —2— against downward displacement or rather against overstraining the interlocking parts between the plates —1— and —2— and at the same time stiffening the main body —1— of the form. 105

The stay rod —4— is also pivoted to the plates —2— and —3— by the same pivotal pin —17— and has its outer end abutting

against the stake —6— which latter is driven into the ground to establish a firm abutment for the adjacent end of the bar —4— to further additionally hold the main body of the form in the desired position as the work of filling in the concrete against the plate —1— progresses.

The stake plate —5— is driven downwardly through the vertically registering slots —14—, —13— and —12— and into the ground to further assist in holding the main parts of the form in operative position and at the same time locking the brace plates —2— and —3— against buckling or flexing at the joint —17—.

The construction shown in Fig. 3 is substantially the same as that shown in Figs. 1 and 2 except that the lower brace plate —3— is omitted. It will be evident, however, that when the brace plate —2— is interlocked with the downwardly projecting portion —10— of the flange —9—, it is supported by said flange against undue downward movement by the engagement of the upturned edge of the tongue —15— with the inner face of the part —10— and the engagement of the shoulders —16— with the outer face of the same part so that when the stay bar —4— is placed against the stake —6— it will form a continuation of the plate —2— to firmly hold the upper end of the plate —1— against outward lateral movement, the base or lower horizontal flange —8— of said plate —1— being of considerably greater width than that of the flange —9— to afford a relatively broad supporting area upon the ground as —B—.

The lower end of the stake plate —5— is properly tapered to a point —18— to enable it to be easily driven into the ground, the openings as —12—, —13— and —14— through which it passes being of substantially the same width as that of the stake plate —5— to assist in holding the main body of the form and other parts against relative endwise movement.

It will be noted that the pivotal connection —17— between the brace plate —2— and the stay bar —4— constitutes a toggle joint which when the parts are adjusted for use assumes a substantially straight line to automatically lock these parts in their adjusted positions for pressing the upper end of the main body —1— against outward displacement assisted, of course, by the abutting of the outer end of the bar —4— against the stake —6—. When the concrete has set against the form, the latter may be removed for reuse at another part of the progressive structure by simply withdrawing the stake —5— and flexing the joint —17— upwardly which will release the form plate —1— and other parts of the mechanism which may then be carried to another part of the work for reuse, it being understood that

the stake —6— may or may not be removed, although the same or another stake will have to be driven into the ground at the place where the form is to be installed.

What I claim is:

1. A form for concrete and analogous work comprising a main plate having an upright wall and outturned flanges along its lower and upper edges, a slotted brace member engaged with the inner and outer faces of the upper flange and a stake passed through the slot in said brace member and adapted to be driven into the earth.

2. A form for concrete and analogous work comprising a plate having an upright wall against which the concrete is adapted to abut, said plate having its upper edge provided with an outturned slotted flange, means for holding the lower edge of the plate against outward movement and additional means having a portion thereof passed through the slot in the upper flange and engaged with the inner and outer faces thereof for holding the upper portion of the plate against outward displacement.

3. A form for concrete and analogous work comprising a plate having an upright wall and outturned slotted flanges along its lower and upper edges, means including a brace plate passed through the slot in the upper flange and engaging the inner and outer faces thereof for holding the upper portion of the first named plate against outward movement, said brace plate having a slot in vertical alinement with that of the lower flange and a stake passed through the slots in the brace plate and lower flange and adapted to be driven into the earth for additionally holding the main plate against outward displacement.

4. A form for concrete and analogous work comprising a main plate having an upright wall against which the concrete is adapted to rest, means for holding the lower edge of the main plate against outward displacement, a stake adapted to be driven into the ground some distance from the main plate and toggle connections between said stake and upper portion of the main plate for holding said upper portion against outer displacement.

5. A form for concrete and similar work comprising a main plate, brace plates having their inner ends engaged respectively with the lower and upper portions of the main plate and the other remaining portions disposed in outwardly converging planes and hinged to each other at their line of intersection.

6. A form for concrete and similar work comprising a main plate, brace plates having their inner ends engaged respectively with the lower and upper portions of the main plate and the other remaining portions disposed in outwardly converging planes and hinged to each other at their line of intersection.

planes and hinged to each other at their line of intersection, a stake adapted to be driven in the ground some distance from the main plate and a brace bar between the stake and 5 pivotal connections between the brace plates.

7. A form for concrete and similar work comprising a main plate having an upright wall and outwardly projecting slotted flanges, slotted lower and upper brace plates disposed at an angle to each other and hinged together at said angle, the lower brace plate being engaged with the lower portion of the main frame, the upper brace plate passing through the slot in the upper 10 flange and engaged with the inner and outer faces thereof and a stake passed through the slots in both brace plates and lower flange 15 adapted to be driven into the earth.

8. A form for concrete and similar work comprising a main plate having an upright wall and outwardly projecting slotted 20

flanges, slotted lower and upper brace plates disposed at an angle to each other and hinged together at said angle, the lower brace plate being engaged with the lower 25 portion of the main frame, the upper brace plate passing through the slot in the upper flange and engaged with the inner and outer faces thereof and a stake passed through the slots in both brace plates and lower 30 flange adapted to be driven into the earth, a stake adapted to be driven into the earth some distance from the main plate and a brace bar interposed between the last named stake and pivotal connection between the 35 brace plates.

In witness whereof I have hereunto set my hand this 17th day of January, 1920.

MARK S. HOTCHKISS.

Witnesses:

W. H. WINDUS,

Mrs. M. S. HOTCHKISS.
